PERCY I. ELIAS AND MICHAEL ANGELO ELIAS, 2D, OF NEW YORK, N. Y.

ELECTRIC-LIGHT FIXTURE.

Application filed January 15, 1921. Serial No. 437,411.

To all whom it may concern:

Be it known that we, PERCY I. ELIAS and MICHAEL ANGELO ELIAS, 2d, citizens of the United States, residing at New York city, 5 in the county of New York and State of New York, have invented certain new and useful Improvements in Electric-Light Fixtures, of which the following is a specification.

Our invention relates to electric lighting fixtures of the indirect or semi-indirect type.

This type of fixture usually includes a ceiling reflector ordinarily made of some 15 suitable plastic composition, and one of the objects of our invention is to provide a construction of lighting fixture in which the reflector is reenforced and supported or suspended from the usual union or nipple 20 which has a firm anchorage in the ceiling.

Another object of the invention is to improve the means by which the shade, forming a part of the fixture, is supported in position beneath the lamp; the shade being 25 readily attachable and removable and not dependent for its support on the lamp socket.

A still further object of the invention is to generally simplify and improve the construction of such lighting fixtures by reducing the number of their parts to the minimum and so coordinating the parts that a maximum of strength with a minimum of weight is obtained.

The form of invention at present preferred by us is illustratively exemplified in the accompanying drawing, in which Fig. 1 is a substantially central vertical sectional view of the improved fixture installed in a ceiling; Fig. 2 is an elevational view of a stirrup forming a part of the construction; and Fig. 3 is a plan view of the shade supporting plate.

Referring by characters of reference to the drawing, A denotes the general plane of the ceiling in which is rigidly held the internally threaded union 10 through which the leading in wires (not shown) pass, as is customary in devices of this general type. Engaging the union 10 and depending therefrom is an externally threaded pipe 11 from which the reflector 12 is supported.

The reflector consists of a suitably shaped plaque, preferably conical with a central opening 13, and may be made of a plastic composition, of fibre or of any other mate-

rial combining lightness and rigidity. According to our invention, we partially embed in the plaque, in the course of manufacturing the latter, a rigid preferably metallic sheet or bar 14 serving as a reenforcing member for the plaque, said bar having an opening through which the lower end of the pipe 11 may pass and the bar being held on the pipe 11 by a lock nut 15 or 60 equivalent securing means. From the foregoing description it will be noted that the reflector is suspended directly from the union 10.

Suspended from the pipe 11 is a stirrup 70 which comprises the cross head or bar 16 engaging the pipe 11, and the lateral depending arms 17. These arms may be threaded at one end, as at 17^a, to screw into the head 16 and their other ends may be 75 provided with heads 18.

The arms 17 support an annular plate 19 from which the shade 20 is suspended. The plate 19 has diametrically opposite key slots 21 therein, whereby the plate may be placed 80 in position by passing the heads 18 of the arms 17 through the larger parts of the slots 21 and then partially rotating the plate until the heads are under the narrower parts of the slots, the interlocking action being 85 somewhat analogous to that of a bayonet joint. Secured to or near the periphery of the plate 19 is a plurality, preferably three, rods 23 the opposite ends of which are hooked at 24 to releasably engage with co- 90 acting hooks 25 formed on the inner ends of studs 26 which pass through the wall of the shade 20. It will be obvious that the hooks 24 and 25 may be easily engaged and 95 disengaged to permit of installation and removal of the shade 20 in a very simple manner.

Plate 19 also serves as a support for the usual socket 22, and to that end the plate 19 is provided with the central opening 27 with which the open end of socket 22 registers. The socket is secured to the plate by screws 28 or their equivalents, and the usual filament lamp 29 is insertible in and removable from the socket in the ordinary 105 manner. The socket 22 is connected with the leading in wires, but as these electrical connections are well known in this art it has not been deemed necessary to illustrate the same.

When the fixture is installed as shown in Fig. 1 the metal bar 14 is not visible so that

the usual ornamental appearance of the device as a whole is in no way marred. The device may be installed even by persons unskilled in this kind of work, it being merely necessary to pass the pipe 11 through the bar head 14 and screw down the lock nut 15 whereby the reflector and its appurtenant parts are secured in position. Thereafter the lamp 29 is inserted in the socket 22 and the shade 20 properly positioned by interengagement of the hooks 24 and 25.

The fixture may be provided with the wire conduit 30 terminating externally of plaque 12 in the switch casing 31 having the pull chain 32 by means of which the switch (not shown) may be operated.

We claim:—

In a lighting fixture, a reflector having a central opening therein, a metal bar embedded in said reflector, and having a portion thereof protruding from the reflector, said portion being spaced substantially from

and disposed over the opening in the reflector and having an opening therein axially alined with the opening in the reflector, 25 and supporting means engaging the said protruding portion through said opening therein to hold the reflector in suspended position, said means comprising a nut having a flange provided with threaded openings, said nut being adjustable against the under surface of the protruding portion of the bar and over a depending wall pipe, and a plate for the opening in the reflector provided with upstanding screws adapted to 35 engage the openings in the flange of the nut to support the reflector, said plate being further provided with an opening to receive the threaded end of a lamp.

In testimony whereof we have affixed our 40 signatures.

PERCY I. ELIAS.
M. ANGELO ELIAS, 2ND.
